PAINT BRUSH GUARD

John Maslaney, Cadillac, Mich.

Application December 9, 1955, Serial No. 552,137

3 Claims. (Cl. 15—248)

This invention relates to a guard attachment for a paint brush and more particularly to such guards for use in painting trim without getting paint on surfaces adjacent the trim. This invention is particularly adapted for trimming around the glass of a window or door.

It is extremely difficult for one not skilled in painting to paint the trim of a window or door without getting a paint on the glass. In fact, it is difficult even for a skilled painter to avoid smearing the glass unless he exercises special care. The exercise of this special care is time consuming.

Various types of paint brush guards have been developed for painting trim or other fine work. However, none of these guards is completely satisfactory. The primary object of this invention is to provide an improved paint brush guard which can be secured to any paint brush enabling even an unskilled person to paint trim and other fine work without smearing adjacent surfaces.

Another object of this invention is to provide a paint brush guard attachment having a guard part normally biased to operative position and easily retractable to inoperative position for replenishing the brush.

Still another object of this invention is to provide a paint brush guard having means for self biasing the guard into operative position and means by which the guard can be retracted with the same hand used to hold the brush.

A further object of this invention is to provide a paint brush guard attachment which can be used on different brushes with the minimum of difficulty.

Another object of this invention is to provide a guard of simple construction and, therefore, low in manufacturing cost. This guard has a minimum number of parts which are readily manipulated for attachment and removal to the brush.

Other objects of this invention will become obvious upon reading the following specification in conjunction with the accompanying drawings wherein:

Fig. 1 is an oblique view of the paint guard attachment in operative position on a paint brush.

Fig. 2 is another oblique view of the brush of Fig. 1 with the guard in retracted or inoperative position.

Fig. 3 is a plan view of the guard mounted on a paint brush showing the guard in operative position.

Fig. 4 is a side elevation view of the brush of Fig. 3 illustrating the guard attached to the brush in operative position.

Fig. 5 is an elevational, central sectional view of the invention taken along the plane V—V of Fig. 3.

Fig. 6 is an elevational, sectional view of the invention taken along the plane VI—VI of Fig. 3.

Fig. 7 is an elevational, sectional view of the invention taken along the plane VII—VII of Fig. 3.

Fig. 8 is a fragmentary, plan view of a modified guard.

Throughout this specification the word "outwardly" is

2

used and shall be taken to mean "outwardly" or away from the center axis of the paint brush.

Briefly, this invention is concerned with an improved guard attachment for paint brushes having a handle part adapted to slidably fit over the paint brush handle. The guard attachment has a guard part adapted to slidably fit over one face of the bristles of the paint brush. An intermediate part connects the handle and guard parts. This intermediate part has an elongated slot extending between the handle and guard parts and means secured to the brush, between the handle and the bristles, and extending through the slot for guiding the guard. A spring holds the guard part in operative position over one face of the bristles. This spring is preferably housed in a rib extending from the handle part. It is attached to the brush and the handle part providing means for biasing the guard part into operative position.

Referring to the drawings, reference numeral 10 denotes a brush having a handle 11 and bristles 13. The bristles 13 are secured to the handle 11 by the head 12. The brush 10 is of conventional design having the bristle part wider than the handle. Thus, the handle 11 tapers inwardly adjacent the head 12, forming shoulders 14.

The guard attachment, although fabricated as one piece, in reality includes three distinct parts: the handle part 30, the guard part 40, and the intermediate part or neck 50. The handle part 30 slidably nests about the handle 11; the guard part 40 covers one side of the bristles 13; and the intermediate part 50 connects the guard part 40 to the handle part 20.

The handle part 30 has a channel-like cross section (Fig. 7) and includes the flanges 31 connected by the bight portion or web 32. The flanges 31 extend downwardly along the sides of the handle 11 while the web 32 portion 32 extends over one face of the handle 11. The entire handle part 30 is of appropriate size and shape permitting it to slide longitudinally along the handle 11. A rib 33 extends outwardly from the web 32. If made of metal, the rib is stamped out to form a housing for the spring 63 whose function will be described more specifically hereinafter. A tongue or hook 34 is struck from the rib into the housing forming an anchor for one end of the spring 63. The entire unit can be cast of metal or plastic, in which case the rib 33 and tongue 34 are formed in the mold.

The guard part 40 includes a plate having an arcuate cutout 41 on each side, intermediate its ends. At one end and toward the handle part 30, the sides of the plate are bent down along the sides of the bristles 13. This forms a channel in the guard part in which the bristles 13 slide when the guard is retracted or projected. The other end 44 of guard 40 is flared outwardly to project well beyond the sides of the brush. The extreme forward end 45 is bent downward. This entire construction permits only the extreme tips of the bristles to be exposed and allows painting right into a corner or up to the edge of the glass without getting paint on the glass. A struck out thumb tab 46 projects outwardly from the web portion 43 of the channel formed by the flanges 42.

The intermediate part 50 forms a neck connecting the guard part 40 and the handle part 30. This intermediate part is flat and narrower than either the handle part 30 or the guard part 40. It is of sufficient length to permit the channel parts of the handle 30 and guard 40 to slide on the handle 11 and the bristles 13, respectively. The intermediate part 50 has an elongated slot 51 extending between the handle part 30 and the guard part 40. The elongated slot 51 extends slightly into the guard part 40 (Fig. 3). Reinforcement ribs can be provided on each side.

The guard attachment 20 is secured to the paint brush

10 by the bolt 60 extending through the enlarged portion of the handle 11. The bolt 60 has a slotted head 61 and a threaded end on which the nut 63 is screwed. Nut 63 can be a wing nut.

The mechanism for biasing the guard to operative position includes the spring 64 and the hook 65 which is secured to the brush by the screw 66. The spring 64 may be any conventional, closed, helical spring having loops on each end for catching the hook 65 and the tongue 34. A staple may be substituted for screw 66.

Attaching the guard to the brush is simple. A hole 70 is drilled through the enlarged portion of the handle 11 for receiving the bolt 60. Then the hook 65 is secured to the brush by the screw 66. This point of securement lies between the hole 70 and the end of the handle part 30. This point of securement for the hook 65 has to be spaced sufficiently far from the hole 70 to permit the guard to slide on the brush without striking the hook 65. After the hole 70 is drilled and the hook 65 secured to the brush, one end of the spring 64 is attached to the tongue 34 and the other end to hook 65. The guard is placed directly on the brush and the slot 51 aligned with the hole 70. The bolt 60 is inserted through hole 70 and slot 51. The spring washer 62 is then placed over the end of the bolt 60, and the nut 63 screwed on. The nut 63 is tightened, causing the head 61 to bear against the intermediate part 50 but leaving sufficient play between the members that the guard will freely slide past the bolt 60. Assembled in this manner, the spring 64 will pull the guard toward the end of the bristles 13, thus causing the guard part 40 to cover one side of the bristles. The length of the slot 51 and the position of the bolt 60 are such that at the end of the guard's travel the bent forward end 45 exposes only the extreme tips of the bristles.

Operation

Both the brush and guard may be manipulated with one hand. When the person painting with the brush desires to replenish the bristles, he presses his thumb against the thumb tab 43 and pulls on the tab toward the handle. This causes the entire guard to retract toward the handle against the bias of the spring 64. This exposes a major portion of the bristles 13 permitting them to be dipped in the paint. After dipping the bristles, the thumb tab is released, resulting in the spring biasing the guard part 40 over the bristles 13 to the position shown in Figs. 1, 3, 4 and 5. The brush is then ready for painting trim and other fine work without danger of smearing adjacent surfaces. The operator paints along the trim with the brush so held that the guard plate is between the trim and the glass or surface to be protected. The guard plate prevents the bristles from touching such glass or surface.

In most cases, one dip of the brush is sufficient to paint trim along one side of a window or door. When the brush runs dry and requires replenishment, the above operation is repeated. It is obvious that this operation is simple, requiring only one hand thus relieving the other hand for holding the object being painted or for helping to maintain the painter's balance. No positive movement of the guard is necessary to move the guard part 40 to operative position. Its positioning is entirely automatic.

When the brush is to be used for painting ordinary surfaces requiring no trim, the guard can be locked in up position by securely tightening nut 63 while the guard is retracted. The guard attachment 20 can be removed by simply removing the nut 63 and bolt 60. The guard is then displaced from the brush and the spring 64 disconnected from hook 65.

It should be evident that this guard attachment is of simple construction. The guard, neck, and handle parts are preferably fabricated of a single piece of sheet metal. The outline of the guard is cut, the channels of the handle part and guard part and the forward end 44 are shaped, and the tongue 34 and thumb tab 43 struck out. This

can be accomplished in a single operation or in several successive operations. The bolt 60, screw 66, spring 64, and hook 65 are conventional elements. The guard attachment 20 can be molded of plastic or other material.

5 The spring 64 and the means for mounting it in the rib 33 of the handle part 30 protect the painter from the spring. It also conceals the spring, improving the appearance of the entire unit and providing a smooth handle. This structure eliminates any need for cutting into or disfiguring the handle.

10 Fig. 8 illustrates a modified form of this invention. The edge of the forward end 44a is inclined at an angle to the longitudinal axis of the brush. Otherwise the structure is the same as that previously described including the bent edge 45a, the thumb tab 43a and the elongated slot 51a. This form is adapted for use on brushes having bristles forming an inclined end. Such brushes are preferred by many operators for trim painting because their shape facilitates painting in corners.

15 A brush equipped with this guard is not only usable for painting trim but has utility in striping operations or anywhere when one color is to be brought up to another.

20 It will be recognized that a screw may be substituted for the bolt 61. Like the bolt, it may be tightened to secure the guard in retracted position.

25 It should be understood that in describing this invention, preferred embodiments have been shown. Other various and different embodiments can be made without departing from the scope of this invention. These embodiments shall be considered to fall within the scope of this invention unless the appended claims expressly delineate otherwise.

30 I claim:

35 1. A guard attachment for paint brushes comprising: a handle part adapted to slidably fit over a paint brush handle; a guard part adapted to slidably fit over one face of the bristles of said paint brush; an intermediate part connecting said handle and guard parts; said handle part having a rib forming a spring housing; an elongated helical spring in said housing; means for securing said spring in said housing to said handle part; and means for securing said spring to said brush handle whereby said guard part is biased to operative position over one face of said bristles.

40 2. A guard for paint brushes comprising: a handle part having a channel shaped cross section of sufficient width to fit and slide on the brush handle; a guard part having a portion with a channel shaped cross section of sufficient width to fit and slide on the bristles of said brush; a

45 45 flat intermediate part connecting said handle and guard parts; said intermediate part having an elongated slot extending between said handle and guard parts; means adapted to be secured to said brush and extend through said slot for guiding said guard; said handle part having a rib extending outwardly from the bight portion of said channel shaped handle part, said rib forming an elongated spring housing extending longitudinally of said handle part; an elongated helical tension spring in said housing and secured at one end of said housing to said handle part; means for securing the other end of said spring to said brush at a point in proximity to the other end of said housing whereby said spring biases said guard part to operative position over one face of said bristles.

50 55 60 65 70 75 3. A guard for paint brushes comprising: a handle part having a channel shaped cross section of sufficient width to fit and slide on the brush handle; a guard part having a portion with a channel shaped cross section of sufficient width to fit and slide on the bristles of said brush; a flat intermediate part connecting said handle and guard parts; said intermediate part having an elongated slot extending between said handle and guard parts; means adapted to be secured to said brush and extend through said slot for guiding said guard; said handle part having a rib extending outwardly from the bight portion of

said channel shaped handle part, said rib forming an elongated spring housing extending longitudinally of said handle part; an elongated helical tension spring in said housing and secured at one end of said housing to said handle part; means for securing the other end of said spring to said brush at a point in proximity to the other end of said housing whereby said spring biases said guard part to operative position over one face of said bristles; and a thumb tab on said guard part by which an operator can slidably retract said guard part to inoperative position 10 against the bias of said spring.
